[57] CLAIM

The ornamental design for a dispensing container or the like, as shown.

DESCRIPTION

FIG. 1 is a front elevational view of a dispensing container or the like showing my new design;

FIG. 2 is a top plan view;

FIG. 3 is a bottom plan view;

FIG. 4 is a side elevational view;

FIG. 5 is a side elevational view showing the side opposite that seen in FIG. 4;

FIG. 6 is a rear elevational view;

FIG. 7 is a front perspective view on a reduced scale; and

FIG. 8 is a fragmentary perspective view of one of the corners thereof.

FIG. 2
